UNITED STATES PATENT OFFICE.

JAMES AILSON NAYLOR, OF GLEICHEN, ALBERTA, CANADA.

DESIGN FOR A WORK-BOX.

49,157.

Specification for Design.

Patented June 6, 1916.

Application filed January 10, 1916. Serial No. 71,368. Term of patent 7 years.

To all whom it may concern:

Be it known that I, JAMES AILSON NAYLOR, a subject of the King of Great Britain, and a resident of the town of Gleichen, in the Province of Alberta, Canada, have invented a new, original, and ornamental Design for Work-Boxes, of which the following is a specification, reference being had to the accompanying drawing, forming part thereof.

The figure is a perspective view of a work box, showing my new design.

I claim:

The ornamental design for a work box, as shown.

Dated at Gleichen, Alta., this 29th day of November, 1915.

JAMES AILSON NAYLOR.
